A. C. MURRAY.

CAN TOP LIFTER.

APPLICATION FILED MAY 9, 1916. RENEWED JUNE 11, 1920.

1,366,272.

Patented Jan. 18, 1921.

Inventor
A. C. Murray,

By *A. Murray Jr.* Attorney

UNITED STATES PATENT OFFICE.

ALEXANDER C. MURRAY, OF TIMARU, NEW ZEALAND.

CAN-TOP LIFTER.

1,366,272.

Specification of Letters Patent.

Patented Jan. 18, 1921.

Application filed May 9, 1916, Serial No. 96,346. Renewed June 11, 1920. Serial No. 388,345.

To all whom it may concern:

Be it known that I, ALEXANDER C. MURRAY, a subject of the King of Great Britain, residing at Timaru, in the Province of Canterbury and Dominion of New Zealand, have invented certain new and useful Improvements in Can-Top Lifters; and I do hereby declare the following to be a full, clear, and exact description of the invention, such as will enable others skilled in the art to which it appertains to make and use the same.

My invention relates to improvements in can top lifters particularly adapted for use in connection with the ordinary type of flange tin tops which are usually lifted by inserting a sharp instrument between the flange and the upper shoulder of the can.

An important object of this invention is to provide a device of the character described adapted for attachment to a can top and including a lever having a fulcrum at one end thereof and a flange extending from the fulcrum and adapted to engage the under side of the flange on the can top, whereby upon moving the lever upwardly, the fulcrum will cause the flange to rise and lift the can top free of the can.

Other objects and advantages of the invention will be apparent during the course of the following description.

In the accompanying drawings forming a part of this specification, and in which like numerals are employed to designate like parts throughout the same,

Figure 1 is a perspective of a top removing device applied to the top of a can, and Fig. 2 is a detail perspective of the same.

In the drawings wherein for the purpose of illustration is shown the preferred embodiment of my invention, the numeral 5 designates a can of the usual construction and provided at its upper side with an annular flange 6 which is U-shaped in cross section and provided with horizontal and vertical portions 7 and 8 respectively. A removable top 9 is adapted to be arranged in the open end of the can and is provided with an annular flange 10 adapted to contact with the annular flange 6. The annular flange 10 of the detachable top 9 is substantially L-shaped in cross section as clearly illustrated in Fig. 1.

As clearly illustrated in Fig. 2, the device is formed from a single piece of wire 22 bent intermediate its ends to form a thumb piece 23. The thumb piece is curved longitudinally for the purpose of affording a grip upon the device for facilitating the removal of the top. Extending rearwardly from the thumb piece 23 is a pair of outwardly diverging arms 24. The rear ends of the arms 24 are bent upwardly as shown at 25 for contact with the inner side wall of the flange 10. Extending from the upright portions 25 and traversing the horizontal portions of the flange 10 is a second pair of arms 26. The arms 26 form the head of the device and are provided at their outer extremities with inwardly extending arms 27 contacting with the under side of the horizontal portion of the annular flange 10. The bight portion 28 connecting the arms 26 and the arms 27 is adapted to contact with the upper surface of the flange 6 upon the pulling upwardly of the thumb piece 23. Extending outwardly from the arms 27 and conforming to the peripheral curve of the annular flange 10 is a pair of embracing arms 29 contacting with the flange 10 as clearly shown in Fig. 1.

In the use of my improved can top lifter, it will be apparent that upon originally placing the top 9 in position, the device is applied thereto.

When it is desired to remove the top 9, the thumb piece 23 is pulled upwardly thus causing the bight portion 28 to function as a fulcrum. It will be apparent that the portion of the top adjacent the bight portion 28 will be raised upwardly thus permitting the removal of the top 9.

While I have shown and described the preferred embodiment of my invention it is understood that such minor changes in construction, combination, and arrangement of parts may be made as fall within the spirit of the invention and scope of the appended claim.

What I claim is:—

A can top lifter formed from a single length of wire looped at its medial portion to provide spaced arms, the web of the arms being bulged upwardly to provide a thumb receiving member, the ends of the arms being bent upwardly and extended forwardly

and having their terminals curved downwardly to constitute a fulcrum, the downwardly extending portions of the arms being bent rearwardly in spaced parallel relation with the forwardly extending portions and having terminals bent laterally in opposite directions and slightly curved to define can embracing arms, which are adapted to en-

gage a portion of the can to permit the top to be readily lifted therefrom. 10

In testimony whereof I affix my signature in presence of two witnesses.

ALEXANDER C. MURRAY.
